AUTOMATIC CONTROL FOR OIL PUMPS
AND THE LIKE

Herman J. Hammerly, New Britain, Conn., assignor to The Trumbull Electric Manufacturing Company, Plainville, Conn., a corporation of Connecticut

Application November 17, 1934, Serial No. 753,455

3 Claims. (Cl. 137—68)

This invention relates particularly to a float and thermostatically operated switch unit and this case is a partial continuation of application Serial Number 705,541 filed by me January 6, 5 1934 entitled Fuel oil supply.

The main object is to provide a control unit for an oil pump, the unit being of such character and construction that it may be readily installed in a pump casing and removed as a unit when 10 desired for the purpose of repair and replacement.

The construction in general embodies a casting containing an electric motor for driving a pump piston which is attached to the unit and is insertable and removable therewith into the 15 fuel supply reservoir which itself furnishes the pump cylinder.

In addition to the motor and pump piston the unit includes a switch for controlling the motor circuit, this switch being thermostatically actuated under certain conditions and also furnished 20 with a float for actuating the switch under certain conditions, this float being also attached to and insertable and removable with the unit into the fuel supply reservoir or receptacle.

This unit also includes for convenience in 25 manufacture and installation an extension cord or cable connection so that in case anything goes wrong with the pump piston or the motor or switch or the float, these parts may be all removed as a unit together with the electric connecting device and replaced with a new unit with 30 a minimum interruption of service.

Fig. 1 is a vertical sectional view showing the 35 principal parts of a construction embodying my invention.

Fig. 2 is a plan view showing the parts with the cover of the receptacle removed.

Fig. 3 is a horizontal sectional view of the 40 switch unit.

Fig. 4 is a vertical sectional view of the switch unit.

Fig. 5 is a transverse sectional view of the 45 switch unit.

Fig. 6 is an exploded perspective view showing the fuel receptacle and the detachable parts embodying my present invention as claimed herein.

This construction is intended to replace the 50 gravity feed bottle and reservoir commonly employed with oil burner stoves using kerosene or fuel oil. The receptacle 10 has the main chamber 12, the constant level chamber 11 and the overflow chamber 13.

The pump has a cylinder 14 which may be formed integral with or separately and attached 55 to the main body of the reservoir and in the

bottom of which is a check valve 15 controlling the inlet. The piston 16 also has a check valve 17. The electric motor 18 which drives the pump may be of any suitable type and is supported in a casing 19 which is detachably secured in the receptacle 10 in any suitable manner as for instance by means of one or more screws 20. The shaft 21 of the motor has a worm (not shown) meshing with worm gear 22 in the casing. This gear is on a shaft 23 which 10 projects outside the casing 19 and has a crank arm 24 connected to the piston 16 by a connecting rod 25.

Liquid is drawn into the main chamber 12 by the action of the pump and flows through 15 the passage 26 into the constant level chamber 11. The flow through this passage is controlled by a needle valve 27 which in turn is regulated by a float 28. This float is pivoted at 29 so that as the float rises and falls it closes and opens the 20 passage 26.

A filter pad 30 is preferably provided so as to remove foreign particles from the liquid which passes through from chamber 12 to chamber 11. This filter pad is preferably removable for convenience in renewal, etc. Liquid normally flows from the chamber 11 through outlet 31 to the burner or other point of consumption. The chamber 13 has an outlet 32 from which the overflow from the chamber 12 may pass back 30 to the source of supply (not shown).

Electric current is supplied to the motor through a cable 33 which contains the necessary conductors and which is positioned by a bushing 34 removably seated in a notch in the edge of 35 the casing 19 and the notch 35 in the edge of the main reservoir. This bushing is held in place by the cover 36 of the receptacle.

The starting and stopping of the motor is controlled by a switch enclosed in a housing 40 made up of an insulating base 37 and a metal cover 38. This switch consists of the thermostatic arm 40 having one end looped around and secured to a support 41 and provided with an adjusting screw 42. The movable end of the 45 arm carries a finger 43 which is hinged at 44 to the movable end of the arm. This finger carries a contact 45 which is adapted to snap back and forth between the abutment 46 and the stationary contact 47, a spring 48 being provided 50 for this purpose.

This switch is actuated by the thermostatic action commonly relied upon in switches of this character. The switch is also adapted to be actuated by a float 50 which is supported on the 55

- end of a bell crank lever or shaft 51, one end of which has an eccentric or cam portion 52 which is adapted to coact with an insulating wearing surface or abutment 53 carried by the movable end of the thermostatic switch arm 40. The end of the crank shaft 51 is pivotally supported in the switch housing. The switch housing is secured in the casing 18 in a suitable manner as for instance by means of a bolt and nut 55.
- 10 One wall of the casing 18 is notched at 56 to allow for the movement of the float lever 51 so that the switch unit and the attached float 50 may be removed without disturbing the other parts of the casing 18 and its contents.
- 15 Under normal conditions the switch is actuated in the manner of a quick make and break switch by the movement of the float 50 when it rises and falls in the main liquid reservoir chamber 12. This float in a standard type mechanism 20 starts and stops the motor when approximately one half pint of fuel is used and under normal operating conditions it requires from one to two minutes, depending upon the lift of the oil, to pump this one-half pint.
- 25 Under abnormal conditions, for instance, when a pipe line is broken or in case the float 50 fills, or in case the tank runs dry, the motor would tend to run continuously because there could be no action of the float 50 to shut off the pump 30 motor.

The thermostatic action of the arm 40, however, is so designed that after a period of approximately five minutes the heat of the motor enclosed within the casing 18 will operate the thermostat and open the circuit of the switch even though the float 50 remains down. This thermostat may be reset automatically or by hand. In the latter case a reset button of conventional type may be employed to extend out 35 side or through the cover and arranged to indicate when the switch is on or off.

Safety precautions as above indicated are of the greatest importance in a construction of this character since the continued flow of fuel oil 40 or overflow of the oil is likely to create a dangerous fire hazard. Since the continued successful operation of the fuel supply is of vital importance to the person relying upon it, it is essential for commercial purposes that the parts 45 of the motor and pump which are likely to be deranged be readily inspected and replaceable so as not to interrupt the continuous operation of the system.

The invention herein described and claimed 50 has been proven to effectively supply the demand for such apparatus.

The enclosure 19 for the motor and delay action thermal means, not only safeguards these parts against coming in contact with the liquid 55 but also localizes the heating of the motor and prevents its ventilation in as free a manner as

might otherwise occur were it not for this enclosure 19 which impedes convection currents of fluid, especially air, around the motor and thermostat. It will be seen that the chamber supplied by the pump not only has a normal discharge passage into the constant level chamber located above the bottom of the first chamber, but both the pump chamber and the constant level chamber have overflow outlets into the overflow chamber 13 where any overflow fuel is returned to the storage tank from which it is drawn by the pump.

I claim:

1. The combination with a tank, of means for supplying liquid thereto, mechanism for controlling said means in response to the liquid level in said tank, a substantially constant level tank formed by a partition in the first tank, said constant level tank having sides located above the bottom of said first tank and said constant level tank being supplied from the first mentioned tank, overflow outlets from each tank, said means including a supply reservoir for the first tank with a pipe therebetween, and a pipe connecting said overflow outlets with said reservoir. 10

2. The combination with a tank, of means for supplying liquid thereto, mechanism for controlling said means in response to the liquid level in said tank, a substantially constant level tank formed by a partition in the first tank, with the 15 sides of said constant level tank located above the bottom of said first tank and said constant level tank being supplied from the first mentioned tank, overflow outlets from each tank, a supply reservoir and a pipe connecting the same 20 with the first tank, a pipe connecting said overflow outlets with said supply reservoir, a valve controlling the flow of liquid from the first tank into the second in response to the liquid level in the second tank, and a filter between said valve 25 and the first tank, said filter being replaceable as a unit and being held by said partition between 30 said first and second tanks. 35

3. A liquid supply tank having partitions dividing it into a main supply chamber, a constant level chamber and an overflow chamber, with overflow outlets from the main supply chamber and the constant level chamber to the overflow chamber, means for supplying liquid to the main supply chamber, means responsive to the 40 level of the liquid in the main supply chamber for controlling the means for supplying liquid to the main supply chamber, one of the partitions having a passage from the main supply chamber to the constant level chamber, means responsive to the 45 level of liquid in the constant level chamber for controlling the normal passage of liquid from the main supply chamber to the constant level chamber and a discharge pipe leading from the overflow chamber. 50

HERMAN J. HAMMERLY.
